(57) **CLAIM**

The ornamental design for a mobile phone shell, as shown and described.

DESCRIPTION

FIG. 1 is a first perspective view of a mobile phone shell showing my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view thereof showing the mobile phone shell in an open configuration;

FIG. 10 is a perspective view thereof showing the mobile phone shell in an alternate configuration; and,

FIG. 11 is an enlarged view of the selected portion 11 in FIG. 2.

The broken lines in FIGS. 2 and 11 delineate a portion of the claimed design that is shown on an enlarged scale in FIG. 11; the broken lines form no part of the claimed design.

1 Claim, 11 Drawing Sheets
